UNITED STATES PATENT OFFICE.

GUSTAVE A. OSTERUD, OF SEBEKA, MINNESOTA.

TOBACCO-PIPE.

SPECIFICATION forming part of Letters Patent No. 640,408, dated January 2, 1900.

Application filed May 17, 1898. Serial No. 680,923. (No model.)

To all whom it may concern:

Be it known that I, GUSTAVE A. OSTERUD, a citizen of the United States of America, and a resident of Sebeka, Wadena county, Minnesota, have invented certain new and useful Improvements in Tobacco-Pipes, of which the following is a specification.

My invention relates to improvements in tobacco-pipes; and it consists of a body and stem which are adapted to collapse so as to form a compact parcel for carrying in the pocket. To prevent the ashes or tobacco from falling into the pocket when the pipe is thus carried, I provide a cover which is adapted 15 to interlock with the stem when the pipe is collapsed, so as to hold the cover and stem closed, and to collect the liquid refuse from the tobacco I provide a cap which is fastened to the lower end of the stem containing a 20 cavity which may be readily emptied.

In the accompanying drawings, forming part of this specification, Figure 1 is a longitudinal cross-section of my improved tobacco-pipe shown with the stem extended in readiness for use. Fig. 2 is a side elevation of the same, showing the pipe collapsed, portions of the same being shown in cross-section. Fig. 3 is a plan view of Fig. 2. Fig. 4 is an enlarged detail view of the cover-plate of the 30 pipe, showing the stem interlocked therewith.

In the drawings, let A represent the body of the pipe, composed of wood or other suitable material, having the bowl 2 for containing the tobacco. A port passage-way 3 connects to the bottom of the bowl and is adapted to register with the port passage-way 4 in the stem B when the stem is extended and the pipe in readiness for use.

The stem B is composed of wood or other 40 suitable material; and it consists of the shank 6, which is bent so as to form the mouthpiece 5, extending to the rear from the body A when the pipe is open. A cap 7 is fastened by screw-thread 12 to the lower end of the shank 45 and is provided with the tapering shoulder 8, which is adapted to engage the corresponding shoulder 9 at the upper end of the passage-way 10 when the stem is extended, as shown in Fig. 1. The dimensions of the passage-way are sufficient, so that the stem will 50 slide freely therein. The passage-way 11 is formed on the rear side of the pipe, in which

the mouthpiece 5 is adapted to rest when the pipe is collapsed. The passage-ways 10 and 11 are adapted to form a continuous passage-way for the stem when the pipe is collapsed. 55

The cap 7 is provided with cavity 14 for collecting liquid refuse from the tobacco and opening 22, leading therefrom, by which said cavity may be emptied. The thumb-screw 15 60 is provided for closing said opening when the pipe is in use. The cap is also provided with port passage-way 21, which is adapted to register with port passage-way 3 in the body A when the stem is extended, and port passage-way 13, which connects the cavity to the port passage-way 4 in the stem. 65

To prevent the ashes from falling out of the bowl when the pipe is placed in the pocket, there is provided the cover-plate 16, having 70 vent-perforations 18 for the admission of air to the tobacco. This plate is pivotally mounted upon the top of the pipe by means of screw 17 and is provided with inwardly-projecting spring-flanges 19 and 20, which are positioned 75 over the passage-way 11 and adapted when the cover and stem are closed to interlock with the mouthpiece 5, and thereby retain the stem collapsed and the cover-plate closed over the bowl. 80

In the use of my improved tobacco-pipe upon removing the pipe from the pocket the stem B is withdrawn from its passage-way and given a half-turn and the tapering shoulder 8 of the stem drawn into engagement with 85 the shoulder 9 of the passage-way 10. When the stem is thus tightly engaged, the port passage-way 4 thereof and port passage-way 3 in the body A then respectively communicate with each other. 90

In collapsing the pipe the stem is turned and closed into its passage-ways, and thus caused to engage and interlock with the cover-plate 16. The cap 7 then projects slightly below the passage-way 10, as shown in Fig. 2, 95 and the screw 15 can be easily removed and the collected liquid refuse emptied by blowing through the stem. For more thorough cleaning the cap is uncrewed from the stem and both removed. 100

It is obvious various modifications of my improved pipe may be constructed without departing from the principles of my invention.

Having described my invention, what I

claim as new, and desire to secure by Letters Patent, is—

1. The pipe, comprising the body, the bowl, the movable stem and the means for fastening said body and stem which have suitable port passage-ways adapted to connect and disconnect with said bowl when the stem is respectively extended and folded; said stem being adapted to extend and fold upon said body for the purposes specified.
2. In a device of the class described, the combination of the body of the pipe, having the bowl therein for containing the tobacco, the stem having a port passage-way adapted to register with port passage-way in the body of the pipe when the stem is in extended position and thereby connect with the bowl of the pipe and cease to register when the pipe is collapsed, and the passage-way in the body portion of the pipe for containing said stem, when collapsed therein, and adapted to sustain said stem when in open position by means of engaging shoulders formed on said stem and passage-way, for the purposes specified.
3. The pipe, consisting of the body A; the bowl 2; the stem which is collapsibly fastened to and adapted to fold upon and extend from said body; and the port passage-ways in said body and stem which are adapted to respectively connect and disconnect with the bowl of the pipe when the stem is extended and collapsed as shown, and for the purposes specified.
4. In a device of the class described, the combination with the body of the pipe, having a bowl for containing the tobacco and a passage-way in its lower portion, having a tapering shoulder; of a stem which is collapsibly fastened to said body and provided with a tapering shoulder coinciding with the tapering shoulder of said passage-way, which shoulders are adapted to engage; the port passage-ways which are formed in said body and stem, adapted to register when the stem is drawn out; and a cap fastened to the lower end of said stem having a cavity for collecting liquid refuse from the tobacco contained in the bowl, and provided with suitable draining means for the purposes specified.
5. In a device of the class described, the combination of the body of the pipe, having a bowl for containing the tobacco and the port passage-way connecting to the same; a stem having a port passage-way communicating with said body-port passage-way; the retaining means for holding the stem in collapsed and extended positions, consisting of a cover, having spring-clips for engaging the stem when collapsed; and the tapering shoulder of the port passage-way in the body of the pipe which is adapted to engage the stem when extended for the purposes specified.
6. In a device of the class described, the combination of the body of the pipe, having a stem
- movably fastened thereto; the cover pivotally fastened to the top of the pipe, having suitable vent-perforations, and the interlocking means for holding the stem and cover closed, consisting of spring-clips formed on said cover which are adapted to engage with said stem when the cover and stem are in closed position, for the purposes specified.
7. In a device of the class described, the combination of the body of the pipe, having the bowl for containing the tobacco, a passage-way coinciding with the shape of the stem, for containing the same, and the stem formed with the bend near the mouthpiece which is adapted to be reversed and then collapsed into said passage-way so as to engage with the interlocking means, consisting of spring-clips, formed on the cover-plate, which is mounted on the top of the pipe; said clips by means of their spring members, retaining said stem closed and said stem thereby holding the cover-plate closed, for the purposes specified.
8. The pipe, comprising the movable stem having the port passage-way; the body having the stem passage-way and the port passage-way which connects with the bowl; said stem and body port passage-ways being adapted to connect and disconnect when the stem is respectively moved to extend from and collapse upon said body, and suitable means for fastening said body and stem when moved to either position, for the purposes specified.
9. A pipe consisting of a body A, having a bowl 2, and a passage-way 10, formed therein and a stem B conforming substantially in shape to said passage-way which is movably fastened to said body so as to collapse and extend from said body, and the port passage-ways 3 and 4 respectively formed in the body and stem; said passage-ways being adapted to register or connect when the stem is extended and cease to register when the pipe is collapsed, for the purposes specified.
10. A smoking-pipe consisting of a body A, having a bowl 2, for containing the tobacco; a stem B movably fastened to said body; the passage-ways 10 and 11 formed in said body, said passage-way 10 and stem B having tapering shoulders which are adapted to engage and the port passage-ways formed in said body and stem, adapted to register or connect, when the stem is drawn out and cease to register when the pipe is collapsed.
11. A pipe consisting in combination with the bowl; of the body and movable stem, having port passage-ways which are adapted to connect and disconnect when the stem is respectively extended and collapsed for the purposes specified.
